(57)

CLAIM

The ornamental design of a speaker as shown and described.

DESCRIPTION

FIG. 1 is a front perspective view of a first embodiment of the speaker, the front perspective view showing our new design;

FIG. 2 is a rear perspective view thereof;

FIG. 3 is a second front perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a left-side elevation view thereof;

FIG. 9 is a right-side elevation view thereof;

FIG. 10 is a front perspective view of a second embodiment of the speaker, the front perspective view showing our new design;

FIG. 11 is a rear perspective view thereof;

FIG. 12 is a second front perspective view thereof;

FIG. 13 is a front elevation view thereof;

FIG. 14 is a rear elevation view thereof;

FIG. 15 is a top plan view thereof;

FIG. 16 is a bottom plan view thereof;

FIG. 17 is a left-side elevation view thereof; and,

FIG. 18 is a right-side elevation view thereof.

The broken lines shown in the figures show unclaimed features and form no part of the claimed design.
